UNITED STATES PATENT OFFICE.

KLATE M. HOLT, OF LYNN, MASSACHUSETTS, ASSIGNOR TO GENERAL ELECTRIC COMPANY, A CORPORATION OF NEW YORK.

GOVERNING MEANS FOR ELASTIC-FLUID TURBINES.

Application filed February 19, 1925. Serial No. 10,385.

The present invention relates to elastic fluid prime movers and more particularly to a means for regulating such prime movers in accordance with wide variations in load, 5 inlet pressure, exhaust or back pressure or speed whereby the load may be carried with maximum efficiency under such operating conditions.

The object of the invention is to provide 10 simple and effective means in connection with an elastic fluid turbine for automatically meeting operating conditions of the character above named.

The operating governor of a turbine in 15 connection with the throttle valve is designed to control the turbine within certain limits and usually serves to maintain substantially a constant speed throughout the load range. Within certain limits it operates to admit elastic fluid in accordance with 20 minor changes in the inlet pressure and back pressure also and may be adjusted to give a considerable variation in speed for a given load. It serves thus to control the 25 turbine over a normal operating range and under substantially normal operating conditions.

For abnormal operation involving wide 30 variations in load, inlet pressure, back pressure, or speed beyond the normal range, the inlet nozzle area, designed for efficient operation within the normal range, serves to limit the efficiency and fails to admit the additional volume of elastic fluid necessary 35 to compensate for greatly increased back pressure or greatly decreased inlet pressure for example.

In accordance with the invention, this 40 limitation is removed and the inlet nozzle area is automatically controlled in accordance with the variable factor to be compensated for while providing at the same time for normal operation, and control by the operating governor throughout the normal and 45 abnormal operation.

The operating condition most often to be met is that involving a varying exhaust or back pressure. For this reason the invention is herein described and illustrated in 50 connection with a turbine which is required to operate with such varying back pressure,

and for a further consideration of what is believed to be novel and the invention, attention is now directed to the accompanying drawing, description thereof and the appended claims.

In the drawing, Fig. 1 is a view in side elevation and partly in section of a small elastic fluid turbine embodying the invention, and Fig. 2 is an enlarged sectional view of a detail thereof.

Referring to Fig. 1, 5 is the turbine casing which terminates at one end in an exhaust hood 6 provided with an exhaust outlet 7, and which at its opposite end is provided with an elastic fluid inlet chamber 8 having a flanged inlet opening 9. The inlet chamber is provided with the usual nozzle plate 10 through which elastic fluid is directed to buckets 11 carried by a first stage bucket 70 wheel 12.

The bucket wheel is carried, together with those of succeeding stages if any, on a shaft 13, on one end of which is located a suitable operating or speed governor 14. This is 75 connected by a lever 15 and an operating rod 16 with a throttle valve 17 of the balanced type which is contained in a valve casing 18 interposed between the flanged inlet opening 9 and an elastic fluid supply conduit 19. 80 The arrangement is such that the governor controls the elastic fluid supply to the turbine, an increase in speed above a certain normal speed causing the throttle valve to be moved from the full open position shown 85 toward the closed position in accordance with such increase in speed. This is the usual method of speed control and the arrangement shown is merely illustrative of 90 one means for effecting such speed control.

An emergency valve 20 is provided in the valve casing between the throttle valve and a short conduit 21 leading from the interior of the valve casing to the inlet opening 9 of the turbine. The emergency valve is adapted to close over the inlet end of conduit 21 when released by a suitable latch 22, thereby cutting off the elastic fluid supply to the turbine.

The arrangement thus far described may 100 be taken as representing any elastic fluid turbine, which is provided with suitable

2
governing means controlling the supply of elastic fluid thereto, and since such turbines and governing means are well known and understood, further description of the same 5 is believed unnecessary.

In carrying out the object of the invention, the turbine is provided with means for automatically increasing the inlet nozzle area as the back pressure on the turbine, 10 that is, the pressure in the exhaust hood increases above a certain predetermined value. This provides for passing an increased volume of elastic fluid through the turbine under such conditions, thereby compensating 15 for the decreased pressure difference between the inlet and exhaust and permitting the turbine to carry its load and rated speed.

In the present example, an additional or auxiliary inlet nozzle plate 23 is provided 20 for this purpose, together with an auxiliary inlet chamber 24 connected therewith, being substantially a duplicate of the main nozzle plate 10 and inlet chamber 8 for said stage.

The auxiliary inlet chamber 24 is connected 25 through a branch conduit 25 with conduit 21 between the valve casing 18 and the inlet opening 9 for the main inlet chamber. It thus receives elastic fluid from the main elastic fluid stream at a point on the delivery 30 or turbine side of the throttle valve in the same manner as the main inlet chamber. The conduit 21 and the branch conduit 25 through which said inlet chambers are supplied, form the legs of a divided inlet conduit for the turbine, and as both conduits are connected to the delivery or turbine side of the throttle valve, the flow of elastic fluid through them is at all times under control of the latter.

40 The connection between the auxiliary inlet chamber 24 and conduit 21 is controlled by a valve 26 located in the branch conduit 25 and provided with a casing 27 integral therewith. This valve is normally closed 45 and is operated by a pressure responsive controlling device 28 which is shown in detail in Fig. 2.

50 Referring to Figs. 1 and 2, the pressure-responsive device comprises a diaphragm casing 29, a pilot valve casing 30 and an operating cylinder 31, all integral with each other and mounted on a base 32. The base is supported above the valve casing 27 on a threaded valve bonnet 33 with which it 55 is connected by integral webs 34. The arrangement is such that a valve stem 35, with which the valve is provided, extends directly up into the cylinder 31 coaxially therewith.

60 The valve stem is axially slidable to open and close the valve 26 and is suitably guided in its movement in passing through the cap 33 and by a bearing 36 integral with the base 32. The valve stem is connected with an operating piston or movable abutment 37

which operates in the cylinder 31. The connection between the valve stem and the abutment comprises a reduced threaded end 38 which passes through the center of the abutment and provides a shoulder 39 beneath said 70 abutment, and a clamping nut 40 which is threaded onto the reduced end 38 and firmly seats the abutment against the shoulder.

The abutment is shown in its lowermost or normal operating position in which the 75 valve 26 is held in the closed position. A coiled spring 41, which surrounds the bearing 36 and which is compressed between the lower side of the abutment 37 and the base 32, biases the abutment upwardly to open the 80 valve. By this means the valve is rendered self opening.

The interior of the cylinder 31 above the abutment 37 is connected with the interior 85 of the pilot valve casing 30 by a passage 42. Opposite the passage 42 and spaced apart with respect thereto substantially equally along the length of the pilot valve casing are two openings through the wall, thereof, to which openings are connected conduits 42 90 and 44.

95 Operating fluid under pressure from any suitable source, such as oil from the pressure oiling system of the turbine for example, is supplied to the pilot valve casing through conduit 43, while conduit 44 serves as a discharge outlet for said operating fluid.

100 Within the casing 30 is a cylindrical pilot valve 45 which is slidable in and closely fits the interior of the casing. Between the ends of the pilot valve is a reduced section 46 which provides an annular passage 47 about it of sufficient length to connect the opening for conduit 43 with the passage 42 when 105 said pilot valve is in the position shown. In this position the end of the outlet conduit 44 is closed by the body of the pilot valve.

110 The pilot valve is movable between the position shown and a certain lower position wherein the body thereof closes the opening for conduit 43 and the annular passage 47 connects the passage 42 with the opening for outlet conduit 44. The pilot valve is moved from one of said positions to the 115 other under control of a flexible pressure responsive diaphragm 48 within the diaphragm casing 29.

120 The diaphragm is clamped at its edges between upper and lower sections of the diaphragm casing 29 and is connected at its center with the extended upper end 49 of the pilot valve. The connection is provided by clamping the diaphragm, together 125 with two reinforcing or stiffening washers 50 between a shoulder formed on said end 49 and a clamping nut 51 threaded thereon, after the manner of the connection between the abutment 37 and the valve rod 35.

130 The diaphragm is sufficiently flexible to

carry the pilot valve between its above-mentioned positions, but is prevented from carrying said valve beyond these positions by suitable stop means located in the diaphragm casing 29. In the present example these comprise a ring 52 and a boss 53 integral with the casing providing an upper and a lower seat respectively for the diaphragm.

10 The ring 52 surrounds an inlet opening 54 to which is connected a pressure line 55. In the present example this pressure line leads to the interior of the exhaust hood 6 thereby admitting the exhaust or back pressure above the diaphragm and placing the latter under the control thereof. The ring 52 is of sufficient depth to prevent the nut 51 from obstructing the opening 54 when the diaphragm is seated against said

20 ring as shown.

The diaphragm is made responsive to any desired range in back pressure by loading or biasing the diaphragm in one direction or the other by suitable means. In the 25 present example atmospheric pressure is admitted to the lower side of the diaphragm through an opening 56 which also serves as a drain outlet for operating fluid leakage from the pilot valve. The lower end 30 of the pilot valve casing is also provided with a drain outlet 57 to which is connected the interior of the cylinder 31 below the movable abutment 37, this connection being provided by an opening 58 through the wall 35 between the cylinder and the pilot valve casing. This opening, together with the drain outlet 57, serves to vent the lower side of the movable abutment, thereby rendering it freely movable in the cylinder.

40 The operation of the present embodiment of the invention is as follows: Assuming that the turbine is operating normally at exhaust pressures below atmospheric pressure, the diaphragm will be deflected to the position shown by the differential pressure. This will carry the pilot valve, as shown, to the upper position in which it cuts off the outlet conduit 44 and permits operating fluid to flow from the inlet conduit 43 through passage 42 and into the cylinder 31 above the abutment 37.

The pressure of the operating fluid is such that it forces the abutment downwardly against the elastic fluid pressure existing beneath the valve 26 and against the action of spring 41, and carries the valve to the closed position in which it is shown. The turbine then receives elastic fluid under control of its operating governor through the inlet chamber 8 and main inlet nozzle plate 10, while the increased inlet area provided by the auxiliary inlet nozzle plate 23 in inlet chamber 24 is cut off. The normal operation for which the turbine is designed is thus unaffected by the auxiliary

inlet means and control therefor, and is carried on with maximum efficiency.

Should the exhaust pressure increase by a predetermined amount, that is, to a value sufficient to overcome the atmospheric pressure beneath the diaphragm, the latter will be deflected by the differential pressure downwardly against the stop boss 53, thereby carrying the pilot valve to its lower position. This closes the inlet end of conduit 43, thereby cutting off the pressure supply and connecting passage 42 with the outlet conduit 44. Upon the release of the pressure the valve 26 will immediately be opened by the action of the spring 41 and 75 the elastic fluid pressure beneath the valve. The operating fluid in the cylinder above the abutment will be forced out by way of passage 42 and outlet conduit 44, the spring 41 being of sufficient strength in itself to 80 do this and to overcome the weight of the abutment, valve and valve stem, together with any friction that may exist.

The elastic fluid inlet area is now increased by the amount provided by the auxiliary inlet nozzle plate, as the elastic fluid now flows through both legs of the divided inlet conduit, that is, to both the main inlet chamber 8 and the auxiliary inlet chamber 24. The additional inlet area is such that 90 the turbine is permitted to receive the necessary volume of elastic fluid to carry its rated load with maximum efficiency against the increased back pressure. It will be seen that for an additional increase in exhaust 95 pressure necessitating a further increase in the inlet nozzle area, a second auxiliary nozzle plate may be provided and controlled in a similar manner.

By the arrangement provided, the additional inlet nozzle area, as well as the main inlet nozzle area, is under control of the operating governor, thus permitting the turbine to operate with the increased exhaust pressure in the same manner as it would 105 normally.

Normal operation is resumed when the exhaust pressure falls below atmospheric pressure and sets up a differential pressure on the diaphragm sufficient to return it to 110 the position shown. The operating fluid is then admitted to the cylinder 31 through the pilot valve, and valve 26 is moved to the closed position.

In case it is desirable to put the auxiliary 120 inlet area into and out of operation between close limits in the differential exhaust pressure, the diaphragm may be loaded with or against the exhaust pressure, under certain conditions, and it will be appreciated 125 that for this purpose, sources of pressure other than the atmosphere may be connected with the inlet opening 56 to supply suitable pressure beneath the diaphragm.

While the invention has been described in 130

connection with what is at present considered to represent the best embodiment thereof, it should be understood that the apparatus shown is merely illustrative and that 5 the invention may be carried out by other means.

What I claim as new and desire to secure by Letters Patent of the United States, is:

1. The combination with an elastic fluid 10 turbine, of means providing a normal elastic fluid inlet area for the initial pressure stage thereof, means providing an additional elastic fluid inlet area for said initial pressure stage, a main elastic fluid supply conduit for 15 the turbine connected with said first named means, a branch conduit connecting the supply conduit with the second named means, a throttle valve in the main supply conduit, means for regulating said valve, a valve in 20 the branch conduit, and means responsive to changes in the turbine exhaust pressure connected with and controlling said last named valve.

2. The combination with an elastic-fluid 25 turbine having a throttle valve, an operating governor controlling said valve, and an exhaust hood, of a divided inlet conduit through which elastic fluid is delivered to the turbine from the throttle valve, a valve in 30 one leg of said conduit, and means responsive to the pressure in the exhaust hood operatively connected with and controlling said valve.

3. The combination with an elastic-fluid 35 turbine having a throttle valve, an operating governor controlling said valve, and an exhaust hood, of a divided inlet conduit through which elastic fluid is delivered to

the turbine from the throttle valve, a valve in one leg of said conduit, said valve being 40 self-closing, and pressure-responsive means connected with said valve and controlled by the pressure in the exhaust hood, which means operates to hold the valve in the closed position when said pressure is within 45 a certain normal operating range.

4. The combination with an elastic-fluid 50 turbine having a throttle valve, governing means controlling said valve, and means providing a certain normal elastic fluid inlet area for the turbine, of means providing an additional elastic fluid inlet area for the turbine, a conduit connecting said means with the throttle valve adjacent the turbine, 55 a valve in said conduit, and means responsive to the exhaust pressure of the turbine connected with and controlling said valve.

5. The combination with an elastic-fluid 60 turbine having a throttle valve, governing means controlling said valve, and means providing a certain normal elastic fluid inlet area for the turbine, of means providing an additional elastic fluid inlet area for the turbine, a conduit connecting said means with the throttle valve adjacent the turbine, 65 a valve in said conduit, and means responsive to the exhaust pressure of the turbine connected with and controlling said valve, a certain lower exhaust pressure causing said device to close the valve and a certain higher exhaust pressure causing said device to open the valve.

In witness whereof, I have hereunto set my hand this 17th day of February, 1925.

KLATE M. HOLT.
